No. 788,363.

PATENTED APR. 25, 1905.

M. MARGOLIN.

DRIVING GEAR FOR SEWING MACHINES.

APPLICATION FILED JAN. 5, 1905.

UNITED STATES PATENT OFFICE.

MEYER MARGOLIN, OF NEW YORK, N. Y.

DRIVING-GEAR FOR SEWING-MACHINES.

SPECIFICATION forming part of Letters Patent No. 788,363, dated April 25, 1905.

Application filed January 5, 1905. Serial No. 239,704.

To all whom it may concern:

Be it known that I, MEYER MARGOLIN, a citizen of the United States, residing at New York, in the county of New York and State of New York, have invented certain new and useful Improvements in Driving-Gears for Sewing-Machines, of which the following is a specification, such as will enable those skilled in the art to which it appertains to make and use the same.

The object of this invention is to provide improved means for driving sewing-machines, a further object being to provide improved means for driving a large number of sewing-machines secured to a table or other support, as is customary in factories of various kinds or classes, and whereby all belts and similar driving devices are dispensed with and whereby any desired part of a given number of machines may be kept in operation while the other machines are not being driven or operated, a further object being to provide an improved driving mechanism for sewing-machines whereby less power is necessary to operate a given number of machines; and with these and other objects in view the invention consists in a driving mechanism for sewing-machines constructed as hereinafter described and claimed.

The invention is fully disclosed in the following specification, of which the accompanying drawings form a part, in which the separate parts of my improvement are designated by suitable reference characters in each of the views, and in which—

Figure 1 is a sectional side view of my improved driving mechanism for sewing-machines and showing a table with one machine mounted thereon and provided with the usual drive-wheel, said drive-wheel being provided with a beveled friction-gear; Fig. 2, a partial section on the line 2 2 of Fig. 1; Fig. 3, a plan view of one part of my improved driving mechanism, a part of the support thereof being shown in section; and Fig. 4, a similar view of that part of the driving mechanism which is connected with the sewing-machine.

In the drawings forming part of this specification I have shown at *a* a cross-section of a table, such as is usually employed in gar-

ment-making establishments where a large number of sewing-machines are employed, and placed on this table is a sewing-machine *b*, provided with the usual drive-wheel *b*² and a beveled frictional gear *b*³, and it will be understood that in practice a number of the machines *b* are or may be placed on the table *a* and secured thereto. The table *a* is provided with any suitable framework or support, which in the construction shown consists of upright members *a*² and horizontal members *a*³ and *a*⁴, the latter of which forms a base, and at any suitable point below the table *a* and below the back portion thereof is mounted a main power-shaft *c*, having large beveled frictional gear-wheels *c*², only one of which is shown, and the gear-wheels *c*² in practice will correspond in number with the number of the sewing-machines *b* employed.

The table *a* is provided rearwardly of the machine *b* with a bearing *d*, and passed through said bearing and through the table *a* at a downwardly and backwardly inclined angle of about forty-five degrees is a tubular casing *e*, having a central box-shaped member *e*² and yoke-shaped end brackets *e*³ and the tubular casing *e*. The central box-shaped member *e*² and the yoke-shaped brackets *e*³ at the end thereof are all composed of two parts, as shown in Fig. 2, secured together at *e*⁴ in the usual or any preferred manner.

Passed longitudinally through the tubular casing *e*, the central box-shaped member *e*², and the yoke-shaped end member *e*³ thereof is a supplemental drive-shaft *f*, composed of two parts *f*² and *f*³, the adjacent ends of which are overlapped in the central box-shaped members *e*², as shown at *f*⁴ in Fig. 1 and also shown in section in Fig. 2, and as thus constructed and connected the separate parts *f*² and *f*³ of the supplemental drive-shaft *f* are free to move longitudinally with reference to each other. The part *f*² of the supplemental drive-shaft *f* is provided with a beveled frictional gear *g*, which is adapted to operate in connection with the bevel gear-wheel *b*³ on the machine *b*, and the part *f*³ of the supplemental drive-shaft *f* is provided with a bevel-gear *g*², which is designed to operate in connection with the bevel gear-wheel *b*².

c^2 on the shaft c , and the gear-wheels g and g^2 are preferably provided with a cover g^3 of leather or similar material, and the gear-wheels b^3 and c^2 may be similarly provided, if desired.

Secured to the end of the part f^2 of the supplemental drive-shaft f within the central box-shaped member e^2 of the casing e is a sleeve h , which overlaps the slidably-connected ends of the parts f^2 and f^3 of the supplemental drive-shaft f and holds said ends in proper position, and mounted on the end of the sleeve h is a tubular cap-shaped rack h^2 , and a similar rack h^3 is mounted on the part f^3 of the supplemental drive-shaft f , and within the rack h^3 is placed a collar h^4 , which is secured to said part f^3 of the supplemental drive-shaft f .

In the bottom of the box-shaped member e^2 of the casing e are mounted two pinions or small gears i and j , and the pinion or gear i operates in connection with the rack h^2 , and the pinion or gear j operates in connection with the rack h^3 . In the bottom of the box-shaped member e^2 of the casing e , adjacent to the pinion or gear i , is a slot or opening k , and the shaft of the pinion or gear i is provided with a crank k^2 , which passes through said slot or opening, and connected with the end of said crank is a rod k^3 , with which is slidably and adjustably connected a supplemental rod k^4 , which is connected at k^5 with a pedal k^6 in the usual or any desired manner.

It will be understood that one of the casings e and all the parts located therein or connected therewith is provided for each of the machines b and each of the wheels c^2 , and each of said tubular casings e is provided below the table a with a supplemental support or brace k^7 of any preferred form and construction.

In the operation of my improved driving-gear for sewing-machines when the operator of a particular machine desires to proceed with his work the pedal k^6 of his machine is depressed, and this operates the pinions or gears i and j , which are turned in opposite directions, and the separate parts f^2 and f^3 of the supplemental drive-shaft f are forced in opposite directions, and the gears g and g^2 , connected therewith, are forced, respectively, into connection with the gear b^3 of the sewing-machine b and the corresponding gear c^2 of the shaft c , and the sewing-machine will be driven, as will be readily understood. The shaft c may be driven by any desired or preferred power mechanism, and it will be understood that this shaft is continually operated. When the operator of any particular machine desires to stop work, the foot is removed from the pedal k^6 , and the pressure of the wheels g^2 on the wheels c^2 being relieved the said wheels will slightly separate, and the movement of the machine b will be stopped, and, if desired, I may employ a spring

or similar device for moving the separate parts f^2 and f^3 of the supplemental drive-shaft f inwardly, and in Fig. 1 of the drawings I have shown a contractile spring m , placed between the table a and the crank k^2 on the shaft of the pinion or gear i , and when the foot is removed from the pedal k^6 the spring m will operate to depress the crank k^2 , as shown in dotted lines in Fig. 1, and the pinions or gears i and j will be turned in opposite directions and so as to force the separate parts f^2 and f^3 of the supplemental drive-shaft f inwardly, this position of said parts being shown in full lines in Fig. 1, while the operative positions of the separate parts of the shaft f and the wheels g and g^2 connected therewith are shown in dotted lines in said figure, and in Fig. 1 of the drawings at each end of the casing e is shown a coil-spring n , which bears against a collar n^2 on each of the two portions f^2 and f^3 of the supplemental drive-shaft f . The said coil-springs n operate always to force the two portions of the shaft f together, and thereby remove the beveled gear-wheels on the shaft f from the beveled gear-wheels b^3 and c^2 , said beveled gear-wheels being again placed in operation by pressure on the pedal k^6 , as will be readily understood.

From the foregoing description it will be seen that by means of my improvement I provide a driving mechanism for sewing-machines whereby one or more of a number of machines operated by a single shaft may be easily and conveniently thrown into or out of operation whenever desired and held in operation as long as desired by simply pressing the foot on a pedal. I also provide a driving-gear of the class specified which is simple in construction and operation and which does not involve the use of belts or similar apparatus, and while I have shown and described the gears or gear-wheels c^2 and b^3 and g and g^2 as beveled and frictional gears or gear-wheels it will be apparent that other forms of gears or gear-wheels may be employed and various other changes in and modifications of the construction herein described may be made without departing from the spirit of my invention or sacrificing its advantages, and I reserve the right to make all such alterations in and modifications of the construction herein described as fairly come within the scope of the invention.

Having fully described my invention, what I claim as new, and desire to secure by Letters Patent, is—

1. In a power-transmitting mechanism, a tubular casing, a supplemental drive-shaft passing through said casing and composed of separate longitudinally-movable parts, said parts of the supplemental drive-shaft being provided with gears at their outer ends, and means for forcing the parts of the supplemental drive-shaft in opposite directions, comprising racks connected with said parts, intermeshing gears mounted in the central por-

tion of the tubular casing and operating in connection with said racks, and a crank connected with one of said intermeshing gears, substantially as shown and described.

- 5 2. In a power-transmitting mechanism, a tubular casing, a supplemental drive-shaft passing through said casing and composed of separate longitudinally-movable parts, gear-wheels connected with the outer ends of said
10 parts of the supplemental drive-shaft, means for forcing said parts of the supplemental

drive-shaft outwardly, and devices for forcing said parts of the supplemental drive-shaft inwardly, substantially as shown and described.

In testimony that I claim the foregoing as my invention I have signed my name, in presence of the subscribing witnesses, this 3d day of January, 1905.

MEYER MARGOLIN
